The ornamental Design for a chair, as shown and described.

DESCRIPTION

FIG. 1 is a prospective view from the front and to one side of the chair;

FIG. 2 is a side elevational view of the chair of FIG. 1;

FIG. 3 is a front elevational view of the chair of FIG. 1;

FIG. 4 is a rear elevational view of the chair of FIG. 1;

FIG. 5 is a top plan view of the chair of FIG. 1;

FIG. 6 is a front prospective view of a second embodiment of the chair of FIG. 1 wherein arms have been added to the chair;

FIG. 7 is a side elevational view of the chair of FIG. 6;

FIG. 8 is a prospective view from the front and to one side of a third embodiment of the chair of FIG. 1 wherein alternate arms have been added to the chair;

FIG. 9 is a prospective view from the front and to one side of a fourth embodiment of the chair of FIG. 1 wherein alternate arms have been added to the chair;

FIG. 10 is a prospective view from the front and to one side of a fifth embodiment of the chair of FIG. 1 wherein alternate arms have been added to the chair;

FIG. 11 is a prospective view from the front and to one side of a sixth embodiment of the chair of FIG. 1 wherein alternate arms have been added to the chair; and,

FIG. 12 is a prospective view from the front and to one side of a seventh embodiment of the chair of FIG. 1 wherein an alternate support pedestal and foot rest have been added to the chair.

The opposite side view of FIG. 2 is substantially a mirror image thereof, the difference being in the absence of the two adjustment handles. The views not shown for the embodiments of FIGS. 6, 8, 9, 10, 11 and 12 correspond to those of FIG. 1, the exception being in the arm rest members of FIGS. 6, 8, 9, 10 and 11 and the foot rest member with the extended pedestal in FIG. 12.
